UNITED STATES PATENT OFFICE.

CHARLES T. HAWLEY, OF GARDNER, MASSACHUSETTS, ASSIGNOR TO SIMPLEX TIME RECORDER COMPANY, OF GARDNER, MASSACHUSETTS, A CORPORATION OF MASSACHUSETTS.

WORKMAN'S TIME-RECORDER.

No. 917,761.

Specification of Letters Patent. Patented April 13, 1909.

Application filed October 25, 1905. Serial No. 284,286.

To all whom it may concern:

Be it known that I, CHARLES T. HAWLEY, a citizen of the United States, and resident of Gardner, county of Worcester, State of Massachusetts, have invented an Improvement in Workmen's Time - Recorders, of which the following description, in connection with the accompanying drawing, is a specification, like characters on the drawings representing like parts.

This invention relates to apparatus for recording on a suitable card or other check the time when a workman enters and leaves his place of employment, the record being thereafter utilized in making up the compensation due the workman for a given period, say one week. In using apparatus of this character each workman has his individual card, and when he enters the factory in the morning his time is recorded on his card, as well as that of his departure at noon, and the return and departure in the afternoon. Not only this, but should the workman leave at any intervening time, for a longer or shorter period, the absences must be recorded in order that when the weekly or daily compensation is figured up such absences may be properly deducted from his actual working time. The use of such cards not only gives to the workman an accurate record of his time, but it greatly facilitates the computation of his wages.

My present invention has for one of its objects the production of a time recorder so constructed and arranged that a single operation thereof records the time whether the workman is entering or leaving the factory, thereby dispensing with any separate device to indicate the "in" or "out" record.

Another object of my invention is the production of novel means for accurately positioning the card in readiness for the record to be made thereon, such positioning being wholly automatic.

Another object of my invention is the production of novel printing or time stamping mechanism, whereby the superposing of one record over another is prevented.

These and various other objects of my invention, and the several novel features thereof will be fully described in the subjoined specification and particularly pointed out in the following claims.

In the present embodiment of my invention the time stamp, meaning thereby a re-

cording or stamping mechanism, which comprehends hour and minute marking or stamping members, is so arranged, in relation to the card on which the record is to be made, that the time record for each day will be made in vertical columns on the card, such columns being arranged in parallelism in the sequence of the days of the week. The positioning of the card for the daily time record is effected in such manner that the earliest record is made nearest the top of the proper column, and the time of subsequent operations of the apparatus will be recorded at intervals farther down the column. The exact time of each operation of the apparatus is thus accurately and plainly recorded, a glance at the card showing whenever the workman entered or left the factory, and the exact period or periods of time he was at work or away. A time movement or clock is utilized to operate the time recording mechanism, in a novel and efficient manner, the operation of the apparatus automatically locking the printing or stamping members of such mechanism at the instant the record is made, to insure absolute accuracy thereof, the manually operated actuator for the apparatus being automatically released from the working parts immediately after the record is made, so that said parts return to normal position independently of any act of the workman. This will appear more clearly hereinafter in the detailed description of the construction and operation of the apparatus.

Figure 1 is a front elevation, partly broken out, of a workman's time recorder embodying one form of my invention, inclosed in a suitable protective casing, the connection between the time movement or clock and the recording mechanism being partly shown where the casing is broken out; Fig. 2 is a view of one of the individual cards or checks used in connection with my time recorder; Fig. 3 is a front elevation of the recording mechanism embodying my invention, and which is located in and concealed by the lower part of the casing shown in Fig. 1; Fig. 4 is a left-hand side elevation of such mechanism, showing the various parts in normal position, and the manually-operated actuator which is seen at the left of the casing in Fig. 1; Fig. 5 is a detail of the means whereby the actuator is released automatically from the various parts of the recording mechanism after the record has been made.

on the workman's card, the actuator being moved by the workman from normal position, Fig. 4, to that shown in Fig. 5; Fig. 6 is a rear elevation of a portion of the mechanism shown in Fig. 1, to more clearly show the actuator, the main shaft turned thereby, and the transmitting connections between the shaft and the various other parts of the apparatus; Fig. 7 is a top plan view of the recording mechanism shown in Figs. 1 and 4; Fig. 8 is a transverse section on the line 8—8, Fig. 3, showing in plan the actuating or motor means for operating the card-positioning instrumentality and a portion of the escapement or let-off which controls or governs such means; Fig. 9 is a vertical section taken on the line 9—9, Fig. 7, looking toward the right, to show in elevation the time printing or recording mechanism proper, and the traversing carriage on which it is mounted, the card-receiver or guide being shown in central vertical section; Fig. 10 is a similar view, on the line 10—10, Fig. 7, looking toward the left, showing the opposite side of the time printing or recording mechanism and its carriage, and the platen-actuating and alarm mechanisms, the bell of the latter being indicated by a dotted circle, the card-receiver being shown in elevation; Figs. 11, 12 and 13 are details of a portion of the time printing or recording mechanism, at the right of the line 11—11, Fig. 7, Fig. 11 showing the normal relation of the hour and minute printing or recording members; Fig. 12 their relative position just previous to a change of the hour member; and Fig. 13 their relative position just after such change has been made; Fig. 14 is a detail of the operating connections between the actuator and the means for making the impression upon the card through the time printing or recording mechanism, the detail being taken substantially on the line 14—14, Fig. 7, looking toward the left; Fig. 15 is a view of a portion of the connection shown in Fig. 14, but in a different position, assumed just about the instant the record is made; Fig. 16 is a view of the same parts, but after the record has been made and the means for making the same have returned to normal position, the position of the parts corresponding to that illustrated in Fig. 5; Figs. 17 and 18 are details of the escapement or let-off device, to be hereinafter referred to; Fig. 19 is a right-hand side elevation of the ribbon-feeding mechanism, the main framework being omitted; Fig. 20 is a top plan view, enlarged, of the platen which coöperates with the time printing or recording mechanism in making the record on the card; Fig. 21 is an end elevation of the platen; Fig. 22 is a horizontal sectional detail through the card-receiver or guide and the axis of the stop-carrier, showing one of the series of stops in operative position with

relation to the card receiver; Fig. 23 is a similar view but showing the topmost stop and the means for controlling the position thereof, said stop being mounted independently of the series of stops, for a purpose to be described; Fig. 24 is a view of the time indicator which is movable with the stop-carrier, and which facilitates setting thereof, the half-hour indications on the said indicator being almost entirely omitted in Fig. 3 to avoid confusion; Fig. 25 is a partial front elevation of a modified arrangement for operating the series of card stops, to be described; Fig. 26 is a transverse section on the line 26—26, Fig. 25, looking down, the series of stops in the modification being substantially like the topmost stop shown in Fig. 23, and being actuated in turn through a rotating member, as will appear hereinafter; Fig. 27 is an enlarged detail of the adjustable connection or coupling between the escapement let-off for the motor mechanism and the time movement, permitting the escapement to be set manually in accord with the time movement, the sectional portion of Fig. 27 being taken on the line 27—27, Fig. 28; Fig. 28 is a top plan view of the said coupling or connection; Fig. 29 is an enlarged detail in plan of a portion of the motor mechanism and the means whereby the daily shifting of the time stamp is governed, such shifting effecting daily a change in the relative position of the time stamp and the card receiver, the controlling cam for said means being also shown; Fig. 30 is a detail on the line 30—30, Fig. 29, looking toward the right, to show more clearly some of the parts which are hidden in Fig. 29; Fig. 31 is an enlarged detail, partly in side elevation and partly in vertical section, of the means whereby the time stamp shifting mechanism is rendered inoperative at the end of the week, to permit retraction of the time stamp to initial position; Fig. 32 is a development of the impressions made by a complete rotation of the hour and minute marking wheels of the time stamp, placed side by side, and Fig. 33 shows in side elevation the relation between the numbers on the hour and minute wheels, to more clearly illustrate the group arrangement of the minute indications or figures. Fig. 34 is a front elevation of the ink-ribbon carriage, to show details of construction not clear in other figures, and Fig. 35 is a rear elevation thereof, both views showing the carriage as detached from the parts of the main frame on which it is supported. The casing 1, Fig. 1, of suitable size and shape to contain the operative parts of the apparatus, has in its upper portion a time movement or clock with exposed dial and hands as usual in time recorders, the bottom of the casing receiving the mechanism to be described for stamping or recording the time upon a suitable card, an opening at 2 in the

casing receiving the upper end of the card receiver or guide. A sight-opening 3 permits a visual indicator to be seen from the exterior, said indicator showing the day of 5 the week.

- The arbor of the minute hand 4 of the time movement has suitably geared to it, see dotted gears 5, 6, Fig. 1, a depending spindle 7 making two revolutions per hour and 10 driving, by like gears 8, a second spindle 9 at the same rate, said spindles being connected by universal joints with extensions 7^x, 9^x, respectively. As will be explained the extension 7^x is connected with and drives the minute-marking member or wheel of the time stamp, while the extension 9^x controls a let-off and escapement for a motor mechanism, and by or through which the hour marking member or wheel of the time stamp is driven. 15
- The let-off is of such construction that the time movement in practice exerts but little driving action thereon, so that said time movement is called upon to drive or actuate only the minute marking member, thereby 20 putting but little additional strain upon the time movement.

Before describing the mechanism the record card, slip or check 10, Fig. 2, will be referred to, the same being preferably an elongated card of suitable stiffness, having at its upper end a heading for the name or number of the employee, and immediately below the abbreviations of the days of the week are printed in a horizontal line across the card, 35 as at 11, Fig. 2. A cross line 12 is ruled on the card below the day headings, and the card is divided by vertical or longitudinal rulings 13 into columns, each corresponding to a day. Horizontal lines at 14 indicate the noon hours of the several days, and at the proper distance below them is another line 15, which may be the six o'clock line, or any other hour for closing, leaving spaces below it in the several columns for overtime or 40 night-work records. In using such cards on my present apparatus the time records of each employee for a given day are stamped or printed in the proper column for such day, the line 12 being a species of index line denoting the set time for beginning the day's work, and by suitable mechanism the relative position of the card and the time stamp is changed at predetermined intervals each day, and a daily change in such relative position is also provided for, as will appear hereinafter. By referring to Fig. 2 it will be seen that the employee "John Smith" had his time for beginning work recorded before seven o'clock each day but Saturday, and 45 then he was late, his time being taken at 7.10, a glance at the line 12 showing whether the employee was on time or late, according to the record being above or below the line. A similar inspection of the lines 14 indicates at 50 once, without actual reading of the records,

whether the employee was on or behind time both when knocking off and returning to his work, thus facilitating the work of the official whose duty it is to make out from the cards the employee's time and the wages due. 70 Further reference to the card will be made hereinafter as may be necessary to properly explain my invention and the operation thereof.

Referring to Figs. 3 and 4, 6 to 8, the operating mechanism is carried by a skeleton frame comprising a bottom plate 16, top plate 17, sides 18, (the latter rigidly connected by a cross-girth 19 and each having a horizontal-faced lug 20), posts 21 firmly securing the bottom and top plates, the latter being secured by extensions 22 to the sides 18. Heavy tie-rods 23, 24 connect the sides, the rod 23 being located back of and just below the girth 19 and forming a fixed track on 80 which moves the carriage on which the time stamp is mounted, the rod 24 connecting the sides near their rear upper corners. A stop collar 25, Fig. 7, is adjustably secured on the rod 23 to limit movement of the carriage at 90 the end of its advance, such advance being effected step by step, daily.

The card receiver or guide, in which the card is inserted and held when the time record is made, is herein shown as an upright, 95 metallic case 26 fixedly secured at its upper end to lugs 27 on the top plate 17, and having a flared mouth 28 which projects into the opening 2 of the casing, see Fig. 1, so that a card may be readily inserted in the receiver 100 and withdrawn therefrom when the record is made. The front wall of the receiver has an elongated, longitudinal opening 29, Figs. 3, 9, 22 and 23, and its rear wall is transversely concaved at 30, opposite the opening, 105 and a series of stops 31 being brought one after another into operative position to project through the opening 29 and form a temporary bottom for the receiver, in the manner shown in Fig. 22. These stops are conveniently made as thin metal plates substantially triangular in shape, each being pivoted at 32 upon an arm 33 secured by its hub 34 on a shaft or carrier 35, in front of and parallel to the receiver opening 29, the arms extending radially from the carrier in parallel horizontal planes, and being arranged in the form of a helix or spiral, see Fig. 3. A lug 36 on each stop enters a slot 37 in its arm, to limit movement of the stop, Fig. 22, and a 110 spring 38 tends to throw the stop outward as far as it can go. The hubs 34 serve to vertically space the arms and the stops carried thereby, and the carrier 35 is so located that as it revolves one stop after another will 115 be brought into engagement with the front wall of the card receiver, and then swung on its sustaining arm into dotted line position, Fig. 22, stretching the spring. At the next 120 advance of the carrier the stop snaps past the 125 130

edge of opening 29 and into the receiver, crossing to the concave portion 30, as in full lines Fig. 22, and then forming a stop to limit the distance a card may be inserted in the receiver. As the stops are in different horizontal planes, best shown in Fig. 3, it will be seen that the effective depth of the receiver depends upon which stop is in operative position, the higher the stop on the carrier the less the depth of the receiver, and consequently the point at which a time record will be made in a "day" column on the card is governed by the stops. I have herein arranged the mechanism so that advance of the carrier is intermittently effected at half-hour intervals, the topmost stop of the series being in operative position from 7.30 to 8 p. m., while the lowermost stop is moved into position at 7 a. m. and so remains until 7.30, when the next higher stop is positioned. As the carrier is revolved the opposite edge of the opening 29 acts to push out the stop, turning it on its pivot 32 out of the opening, the spring 38 resuming control as the stop 25 clears the card receiver.

In Fig. 4 I have shown only the lowermost arm and its stop, to avoid confusion, the helical arrangement being indicated by the dotted line.

A cam-like arm 39, Fig. 23, is secured to the carrier above the top-most one of the arms 33 to at times coöperate with a pin 40 depending from a plate 41 which with a stop-plate 42 is pivoted at 43 on the top 17 of the frame adjacent the upper end of the opening 29, a spring 44 normally holding the two plates in the position shown in Fig. 23 against a depending stop 45. A bow-spring 46 connected at its opposite ends to the two plates 41, 42, respectively, serves to normally cause them to move in unison, and when the cam periphery of the arm 39 engages the pin 40, said plates will be swung inward so that the enlarged end of the plate 42 will enter the card receiver, and act as a stop, so long as the plate is held in such position. If a card should be accidentally left in the receiver at the time the cam arm 39 operates, the stop-plate 42 would be held by engagement with the card, but the plate 41 would be free to move, the spring 46 being flexed to permit such movement, thereby preventing any breakage of these parts. This stop 42 is, in the apparatus herein shown, moved into its operative position at 8 p. m., and so remains until at midnight the cam 39 releases it, and the spring 44 retracts it into inoperative position, such as shown in Fig. 23. Any records between 6 and 8 p. m. will be made in the portions of the day columns below the transverse line 15. If any work is done from 8 p. m. till midnight, the time record will be made in one of the divisions 15^x on the card, see Fig. 2. From midnight to the time 65 the lowest one of the series of stops 31 is po-

sitioned, viz., at 7 a. m., there are no stops coöperating with the card receiver, as none are necessary during that period and any record made between midnight and 7 a. m. appears in the single space above the line 12. 70

The carrier 35 is mounted in bearings in the top and bottom plates of the main frame, and below the stop-carrying arms it is provided with a time indicator, shown in Fig. 24, and consisting of a drum 47 on the periphery of which are half-hour indications, as for instance 6.30 to 7, 7 to 7.30, etc., a shield 48 secured to the frame having a slot through which one of the time indications can be seen, the indicator being so arranged 80 that the half-hour period visible through the slot of the shield indicates which particular one of the stops is then in its operative position. This time-indicator is used only when setting the apparatus, as ordinarily the casing incloses the indicator.

The pinion 49 and gear 50 are fixedly secured to the carrier below the indicator, best shown in Fig. 29, and the gear 50 is provided on its upper side with a cam 51^x presenting 90 an irregular portion at 51 for a purpose to be described, the under side of the gear 50 having attached to it a smaller gear 52 in mesh with the primary gear 53 of a motor mechanism operated by a coiled spring 54, the spring being wound by means of a spindle 55 clearly shown in Fig. 3, the upper end of the spindle being so shaped that a winding key can be readily applied thereto when necessary. Through the gears 53 and 52 the carrier is rotated, and in order that the same may be operated intermittently, I have provided an escapement for the motor mechanism, and a let-off for such escapement. 95

A pinion 56 on a horizontal shaft 57 suitably supported in bearings on the bottom plate of the frame meshes with the gear 50, the shaft 57 having fast upon it a disk 58 provided with three pins 59, disposed as shown in Fig. 17, the pins, however, projecting beyond the opposite side of the disk from that shown in said figure, and for a purpose to be described. Beyond the disk a six-pointed star or escapement wheel 60 is secured to the shaft, its points being arranged 110 to coöperate with a let-off, shown as a worm 61 of very sharp pitch, mounted on a shaft or spindle 62, and operatively connected with the extension 9^x hereinbefore referred to, controlled as to its rotation by the time 115 movement. The spring of the motor mechanism always tends to rotate the shaft 57 and the escapement wheel 60, in the direction of the arrow Fig. 17, so that one of the points of said wheel is maintained in engagement with 120 the worm let-off 61, until by rotation of the latter, that point is released, thereby permitting the escapement wheel, and consequently the motor mechanism, to operate 125 until the next point of the escapement wheel 130

engages the let-off. As has been stated, the extension 9^x makes one complete revolution every half-hour, and the steepness of pitch of the worm acts in practice to assist the time 5 movement in rotating the let-off, so that any drag or strain on the time movement is entirely obviated. As the motor mechanism is permitted to advance, at half-hourly periods, it will be manifest that the carrier and 10 the stops mounted thereon will be rotated at corresponding intervals, to thereby change the effective depth of the card-receiver correspondingly.

The pins 59 are arranged to coöperate with 15 a notched, six-faced escapement 63, separately shown in Fig. 18, the faces 64 being beveled to coöperate with the face of the disk 58, and thereby lock the escapement 63 between movements, the pins 59 coöperating 20 with the notches to rotate said escapement, but as there are only three pins the escapement 63 (and the shaft 65 on which it is mounted) will be rotated at half the speed of the shaft 57, and the parts controlled there- 25 by. In other words, while the stop-carrier is advanced by the motor mechanism at half-hourly intervals, the shaft 65 will be advanced at hourly intervals, and between the advances, it will be held from rotation by the 30 locking coöperation of the disk 58 and the faces 64 of the escapement 63. The shaft 65, clearly shown in Fig. 8, has an attached pinion 66, in mesh with a gear 67, on a vertical shaft 68, made in three parts as shown in 35 Fig. 10, connected by universal joints, so as to afford flexibility, the lower member being mounted in a fixed bearing bracket 69, and the upper member 70 being mounted in bearings 71 on the time stamp carrier to be 40 referred to, the shaft member 70 having an attached gear 72, which by meshing with a gear 73 effects rotation of the hour-marking member or wheel of the time-stamp. The hour wheel is thus driven or actuated step- 45 by-step at hourly intervals by or through the motor mechanism, while the minute marking member or wheel is as will appear hereinafter driven by the time movement, and normally in unison with the minute hand thereof.

50 Referring to Figs. 14, 27 and 28, I have provided a coupling between the extension 9^x and the let-off shaft or spindle 62, whereby the let-off can be set or adjusted with relation to the time movement in a convenient 55 and accurate manner. A disk 74 fixedly secured to the spindle 62 is held against a similar disk 75 by means of a clamp-screw 76 which passes through a segmental slot 77 in the disk 75, and into the lower disk 74.

60 The upper disk is provided with a hub 78 radially notched at 79, and loosely receiving a short shaft 80 coupled at its upper end to the lower extremity of the extension 9^x , and rotating in fixed bearings 81 on the frame, a 65 sleeve 82 fast on the short shaft carrying a

latch 83 supported to enter the notch 79, to lock the shaft 80 with the disks. The peripheries of the latter are graduated, as shown in Fig. 27, so that a very accurate adjustment can be made. By retracting the latch 70 75 83, the let-off mechanism is entirely disconnected from the time movement, as will be manifest, and if a rough setting is desired, the spindle 62 can be turned one or more times by hand to set the let-off, and then by 75 releasing the clamping screw 76, the two disks can be adjusted with relation to each other, and by means of the graduations the let-off can be set with accuracy to accord 80 with the time movement, after which the clamp screw is set up, clamping the two disks together, and so long as the latch is in place the time movement will be operatively connected with the let-off.

Referring to Figs. 6 and 7, a rod 84 is 85 rigidly attached to arms 85 fulcrumed at 86 on adjustable blocks 87 screwed to the upper portions of the frame sides 18, fore and aft adjustment of the blocks 87 being effected by loosening the set screws 88 and moving 90 up or down a wedge 89, the latter working in a recess in its adjacent block, so that the rod 84 can be adjusted in a fore and aft direction, to thereby regulate or adjust the position of the time stamp carriage, relatively to the 95 card receiver when the carriage is moved to the printing point. The latter consists of two rigidly connected, substantially L-shaped sides 90, each side having at its lower end a depending bracket 91, see Figs. 9 and 10, 100 said brackets embracing the guide rod or track 23, hereinbefore referred to, and traveling thereon by means of sheaves or rolls 92, the rear upper ends of the carriage sides having cam surfaces 93 to at times coöperate 105 with the swinging rod 84, rolls 95 mounted on the carriage being adapted to travel on said rod when the same is at rest. The said rod 84 acts in the nature of a follower, co-operating with the cams or cam surfaces 93. 110 On one of the carriage sides, the bearing bracket 71 is mounted, said bracket supporting the upper portion 70 of the actuating shaft hereinbefore described, which drives the hour-marking wheel. A rod 96 rigidly 115 connects the upper ends of the carriage sides and on said rod is rotatably mounted the hub 97 of the hour-marking member or wheel H, see Fig. 7, the gear 73 being fast on the hub. The hour-wheel H is provided on 120 its periphery with printing type, twenty-four numbers being equally disposed around the periphery and running from 1 to 12 inclusive for the a. m. hours and from 1 to 12 inclusive for the p. m. hours, the development of an impression of the complete 125 periphery of the hour-marking wheel being shown in Fig. 32, at H x . I have omitted in the other figures of the drawing the hour figures on the wheel H to avoid confusion. 130

By reference to Fig. 32, it will be seen that the p. m. hours are distinguished by a short dash underneath each one, although any suitable distinguishing mark may be used.

5 A ring-gear 98 and a centering ratchet 99, clearly shown in Fig. 10, are attached to the outer side of the hour wheel, and rotate therewith, the ring-gear meshing with the pinion 100 fast on a shaft 101 rotatably 70 mounted in the carriage, and on which shaft 10 is secured a toothed stop-wheel or stop 102, clearly shown in Figs. 11 to 13.

A rock-shaft 103 mounted in the upper end of the carriage has an attached arm 104 15 provided with a pawl 105 adapted to at times coöperate with the ratchet 99, the spring 106, see Fig. 10, acting on the down-turned end 107 of said pawl-arm to normally maintain the pawl in its inoperative position, 20 Fig. 10, the rock-shaft having at its opposite end a rigidly connected arm 108, see Fig. 9, on which is fulcrumed at 109 a second arm 110, provided with a pawl 111, a spring 112 normally acting to hold the lower end of the 25 arm 110 against a stop 113. When the shaft 103 is rocked, both pawls will be moved into operative position, under normal conditions, but as will be referred to hereinafter, should the pawl 111 lodge on the top of one of the 30 teeth of its ratchet, the arm 110 can then give, swinging on its fulcrum 109. This gives a backward movement to the pawl 111 if its downward movement is checked by lodging upon the point of one of the ratchet 35 teeth. This draws the minute wheel M into coöperative position with the hour wheel H while the pawl remains on the top of the tooth. The ratchet 99 is so set with relation to the hour figures on the wheel H that 40 whenever the pawl 105 is depressed to engage the ratchet one of the hour figures will be positively centered, and locked in position for printing, the locking taking place before the carriage is bodily swung forward 45 to make the impression upon a card in the card-receiver.

The minute marking member or wheel M is peripherally divided into sixty equal parts, and type representing the numbers from 1 50 to 59 inclusive and zero, is arranged upon the periphery but in a peculiar manner, the figures being arranged in groups, and herein I have provided for four such groups of fifteen numbers each. Referring to Fig. 33, the 55 radial lines m divide the periphery of the wheel into sixty equal parts, but the type numbers from 0 to 14 inclusive, and indicated at m^x are arranged at one side of the lines m , while from 15 to 29 inclusive they are on 60 the opposite side, as indicated at m' . From 30 to 44 inclusive the group of numbers is on the same side of the radial lines as the group m^x , and from 45 to 59 inclusive such group corresponds to the arrangement of the 65 group m' . A ratchet 114 is rigidly attached

to the sides of the minute marking wheel M, and with this ratchet the pawl 111 coöperates to center and lock the minute-marking wheel at the time of printing. The grouping of the numbers on the minute wheel prevents confusion or over-stamping on a card when the time record is taken, for the type numbers on the hour-wheel are symmetrically disposed with relation to the radial lines h on the hour-wheel, see Fig. 33, and when the two wheels are locked, a radial line on the minute wheel will lie in the plane of one of the radial lines on the hour wheel. If the time record is made in the first or the third quarter of an hour, in the present arrangement, the hour will be indicated on the card and the particular minute will be printed opposite the upper half of said hour mark, whereas if the minutes are in the second or fourth quarter of such hour, the minute record will be stamped on the card opposite the lower half of the figure.

Referring to Fig. 2, it will be seen that the employee came to work five days of the week before 7 o'clock, so that all of the records are 90 above the line 12, and as they were in the last quarter of the hour, the various minute records are opposite the lower half of the hour 6. On Saturday the employee was late, coming in at 7.10, and such hour is indicated below the line 12, and as the time was in the first quarter the minute record is 95 printed opposite the upper half of the hour 7. It will be supposed that on one of the days, as for instance Tuesday, the employee left 100 his work at 9.12, his record being marked on the card, at the proper place, and returned at 9.25, inasmuch as he went out in the first quarter of the hour, the minute indication is recorded opposite the upper half of the hour 105 figure, and as he returned in the second quarter the minute indication is marked opposite the lower half of the hour figure, showing at a glance that the employee was away from his work from 9.12 to 9.25. Should the employee leave and return within the same 110 quarter of the hour, it will be manifest that the two minute indications will be superposed, but that is unobjectionable, as it shows on its face his absence, and also that it 115 was less than fifteen minutes, it being customary in factories to dock for at least fifteen minutes if the employee is absent from his work a less time. Inasmuch as the hour wheel is advanced at the end of each hour, 120 while the stops coöperate half hourly with the card receiver, it will be manifest that if a record is made in the first and second halves of any hour the hour figure recorded on the card will, in the second half of the hour be 125 below that of the figure recorded in the first half. Suppose a record is made at 9.10 o'clock, and another at 9.35, the two nines will be displayed one above the other on the card, and as the first record occurred in the 130

first quarter of the hour the "10" will be opposite the upper half of the upper figure 9. As the second record was made in the third quarter of the hour the minutes' record, viz: 5 "35" will be opposite the upper half of the lower figure 9. By the action of the series of stops it will thus be seen that each hour space on the card is really divided into first and second halves, and the further subdivision 10 for the location of the minute record gives a clear and unmistakable reading of the record. In Fig. 2 I have shown on the Wednesday column an "out" record at 9.10 and an "in" record at 9.35, to clearly illustrate the foregoing, showing that the employee was absent twenty-five minutes. The stop 42 which cooperates with the card-receiver from 8 p. m. to midnight prevents any registration or recording on the morning portion of the card, 15 should a record be made between the hours named, all records after 8 p. m. being located at the bottom of the card between the lines 15^x, Fig. 2. It is necessary that this stop should remain operative until midnight, because at that time the shifting of the time stamp takes place to change its position with relation to the card-receiver, and pass from one day of the week to the next, a record in 20 the wrong daily column on the card being thereby prevented.

The lower end of the extension 7^x is connected by a combined sleeve and universal joint 115 with a short shaft 116, see Fig. 9, mounted in bearings in a bracket 117 on the 25 adjacent side of the carriage, said shaft having at its lower end a beveled gear 118 meshing with another gear 119 on a driving member or sleeve 120 rotatable on the rod 96, and interposed between the adjacent side of the 30 carriage and the minute wheel, said driving member having at its inner end a radial lug 121, clearly shown in Figs. 11 to 13, and two swinging abutments 122 fulcrumed on the minute wheel are normally held by a spring 35 123 in engagement with opposite sides of the lug, so that under normal conditions the minute wheel will be rotated by and in unison with the driving member 120, the latter being actuated or driven by and in unison 40 with the time movement, as will be manifest.

A lost motion or yielding connection is thus provided between the time movement and the minute wheel, permitting a temporary stoppage of the latter with some lost motion, 45 without interfering with the operation of the time movement. This lost motion connection is designed to prevent an employee from stopping the time movement if he should partially actuate the recorder and endeavor by 50 holding on to the actuator to stop the time movement or clock, for the lost motion connection referred to will permit a stoppage of the minute hand for several minutes without affecting the time movement. If the minute 55 wheel is held from rotation, the driving mem-

ber 120 will continue to rotate, and the leading abutment 122 will be moved ahead by the lug 121, but as soon as the minute wheel is released, the spring 123 acts to draw the two abutments together into co-operation with the lug, and thereby the minute wheel is again set or positioned properly with relation to the time movement.

I have provided means whereby the minute wheel record at the beginning of the hour cannot by any possibility indicate the new hour and fifty-nine minutes instead of the new hour and no minutes, and I also prevent the possibility of the minute record at the end of the hour indicating the current hour and no minutes, instead of the current hour and fifty-nine minutes.

It will be remembered that the hour wheel H is advanced at the end of each hour, to bring the proper hour figure into position for recording, the toothed stop 102 being rotated step by step with the hour wheel, and between the changes of the latter a tooth of said stop stands in the position shown in Fig. 11, in the path of the outer end of a pawl 124 pivotally mounted on the minute wheel, and normally held by a spring 125 against a stop 126 which projects outwardly from the said minute wheel, a second inwardly projecting stop 127 on the ratchet 95 limiting movement of the pawl against the spring. A gravity pawl 128 is pivotally mounted on the ratchet 114 near its circumference, and is free to play between the stop 127 and a pin or projection 129, shown in dotted lines, suitably mounted on the inner face of the ratchet, the free end of the pawl being bent or hooked at 130. As the end of an hour approaches, the movement of the minute wheel brings the pawl 124 into engagement with the operatively positioned tooth of the stop-wheel 102, the pawl spring yielding until the stop-pin 127 brings up against the said pawl, so that the further advance of the minute wheel is prevented, such advance, of course, being due to the operation of the time movement. The stoppage and locking, as it were, of the minute wheel is effected at the fifty-ninth minute of the hour, and at such time the parts are in the 100 position shown in Fig. 12, the hooked end of the gravity pawl resting on the tooth of the stop-wheel, but for the time being performing no function. The minute wheel is locked as described until the stop-wheel is advanced with the change of hour by the hour wheel, so that it is impossible to make a record of the hour and no minutes previous to the change of hour, and the only record 105 which can be made until such change will be 110 the hour and fifty-nine minutes. When the hour is changed the hour wheel advances one step, and the stop-wheel 102 advances in like manner, releasing both pawls and bringing a fresh tooth into operative position, the 115 120 125 130

pawl 124 being instantly swung out of the way by its spring 125, into normal position shown in Fig. 13, while the bent end 130 of the gravity pawl lies in the path of the stop tooth then coming into position and is forced onward thereby, carrying the minute wheel M with it, this motion being assisted by the stress in the lost motion or self-setting connection between the time movement and the 10 minute wheel, pawl 128 then resting against pin or lug 129. In this position of the parts, it will be seen that the minute wheel M is locked by coöperation of the stop-wheel and gravity pawl from any retrograde movement, and at such time the zero on the 15 minute wheel is in position to make a record, if the time stamp is operated. If, therefore, a record is now made, the new hour and no minutes will be indicated, and by no possibility can a record be made at the beginning 20 of the new hour indicating the new hour and fifty-nine minutes, instead of the proper record of the new hour and no minutes. Should the minute wheel, be detained just 25 previous to the hour change,—as is permitted by the lost-motion connection so that the gravity pawl 128 is not in position to be caught and forced onward by the new stop tooth on wheel 102—said tooth may be 30 found positioned ahead of the pawl 128, the pawl 124 having been released and swung forward by its spring. When the minute wheel is released, the lost-motion or self-setting connection between the time movement 35 and the minute wheel automatically advances the latter carrying the gravity pawl over the freshly positioned stop tooth in wheel 102—and dropping it in operative position to act behind said tooth and prevent 40 backward movement of minute wheel. The two locking operations described take place just prior to and just after every change of hour respectively, so that at such times an absolutely accurate record is made, if the 45 time stamp be operated.

For certain purposes for which time stamp wheels are used—the two swinging pawls 124 and 128 may be replaced by a single fixed stop pin in minute wheel M coöperating with 50 the stop-wheel, and I do not wish to limit myself to the particular combination of pawls forming the stop or lock here shown. To effect such operation, the rod or cam follower 84 is swung upward, traveling over the 55 cam surface 93 of the time stamp carriage, and swinging the latter forward on the supporting and guide rod 23, to force the hour and minute marking wheels against an inked ribbon, and to press the latter through an 60 opening 30° in the back of the card receiver, a platen to be hereinafter described at such time being automatically moved forward so that the card is pressed toward the printing type and the latter toward the card. The 65 operation of the cam and follower holds the

carriage stationary when the platen is moved into operative position.

A main or operative shaft 131 is mounted to rock in suitable bearings in the frame-sides 18, said shaft having fast upon it an 70 arm 132, see Fig. 6, connected by a link 133 with one of the rocking arms 86 to which the rod 84 is attached, so that when the shaft 131 is turned in the direction of the arrow 134, Fig. 6, the rod 84 will be raised and will move 75 the time stamp forward to make a record.

A yoke 135 is loosely mounted on the main shaft 131, and is positioned by collars 136, 137, a spring 138 having one end attached to the collar 136, the other end of the spring being attached at 139, Fig. 6 to the yoke, the latter having an elongated cross-bar 140.

A link 141 is hooked at its lower end at 142, see Fig. 9, around the cross-bar 140, the upper end of the link being pivotally connected 85 at 143 with one of the arms, as 108 fast on the rock-shaft 103, so that when the main shaft is operatively turned the movement of the yoke will act to pull down the link, and thereby bring both of the pawls 105 and 111 90 into coöperation with the ratchets attached respectively to the hour and minute marking wheels, centering the same and locking them together, in readiness for the impression to be made, the centering being effected before the 95 complete angular movement has been given to the shaft 131, so that the spring 138 yields as such angular movement is completed. A suitable guide 144, on the time stamp carriage, coöperates with the link 141 to guide it 100 in its movement and also to cause it to move back and forth laterally with the carriage, as the latter is shifted from day to day. The cross-bar 140 of the yoke is of sufficient length to permit the shifting movement of 105 the carriage and the link 141.

A short depending arm 145 secured to the main operating shaft receives loosely the rear end of a rod 146, the front end of which is pivoted to a crank arm 147 on an upright 110 shaft 148 supported in suitable bearings, and having attached radial fingers 149, three of such fingers being shown in Fig. 4, the free ends of the fingers being adapted to move into and out of notches 26 $^\circ$ in the adjacent 115 side wall of the card-receiver. A spring 150, see Fig. 10, is coiled around the rod 146, and attached thereto at one end, and at its other end to the arm 145. When the main shaft is turned to operate the apparatus, the rod 146 is drawn backward, thereby turning the shaft 148 and swinging the fingers 149 inward and against the adjacent upright edge of a card, if the latter has been placed in the receiver, the spring 150 then expanding as 120 the operative movement of the main shaft is completed. The object of these fingers is to align the card in the receiver in proper position relative to the impression point of the time stamp or recorder, the fingers pushing 125 130

the card laterally against the opposite side wall of the receiver and acting to grip or hold the card tightly in such alined position, so that when the record is made, it will be in its proper day column upon the card.

A strong spring 151, see Figs. 6 and 19 is attached to the bottom plate 16 of the frame, and to an arm 152 fast on the main shaft, to return the latter to normal position after the recorder has been operated, and to prevent shock upon such return, I have shown in Figs. 6 and 8 a damping or cushioning device comprising an air cylinder 153 in which operates a suitable piston, the rod 154 therefore being controlled by a link 155 fulcrumed at its upper end on the cross-rod 24, and operated by means of a bell-crank and link connection 156, 157, the bell-crank being rocked by means of a link 158 eccentrically connected with the main shaft. Any other suitable damping or cushioning device, however, may be employed, the latter of itself being of well known construction and forming no part *per se* of my present invention.

The main operating shaft 131 is rocked by means of a handle 159, shown in Fig. 1 at the left of the casing, and I have provided a peculiar and self or automatically releasing coupling between the handle and the shaft, so that when the handle has been moved forward far enough to effect the proper operation of the mechanism, it will be disconnected or uncoupled from the shaft, the latter immediately returning to normal position, so that if the handle should be held forward, no stoppage or derangement of any of the parts of the mechanism could result. The end of the shaft projects a considerable distance beyond one of the frame-sides 18, as shown in Fig. 6, and on this projecting end is loosely mounted the long hub 160 of the actuating handle, said hub adjacent the frame having an enlargement 161 which is overlapped by a retaining ear 162 screwed onto the frame-side and preventing endwise withdrawal of the handle from the shaft. A stop-lug 163 on the enlargement limits the rearward movement of the handle, and a toe 164 cooperates with the retaining lug to limit forward movement.

A toggle-actuator is carried by the handle, and as herein shown comprises a short shaft 165 mounted in the hub enlargement 161 with a toe 166 fast on the outer end of the shaft and a wiper 167 fast on its inner end, see Figs. 15 and 16, the toe being normally held against the notched base of a detent 168, as shown in Fig. 4, said detent having a depending extension 169 for a purpose to be described. A spring 170 acts to hold the toe in the position shown in Fig. 4, and as the detent is pivotally mounted at 171 on the hub enlargement 161, it will be manifest that when the handle 159 is pulled forward or to the right, viewing Fig. 4, the toggle actuator

will move therewith bodily, and the wiper 167 will be moved from the position shown in Fig. 14 to that shown in Fig. 15, moving at such time as if it were rigid with the handle. A toggle comprising links 172, 173, is interposed between the base plate 16 of the frame and an arm 174 fast on and extended rearwardly from the operating shaft 131, the link 173 being connected with said arm, and toggle link 172 having a fixed fulcrum at 172*. In the normal position the parts are as shown in Fig. 14, and when the handle is operatively moved, the toggle actuator is swung downward and rearward into the position shown in Fig. 15, the wiper acting upon the toggle at the joint thereof, tending to straighten it, and thereby the shaft 131 is turned in the proper direction, indicated by the arrow in Fig. 15, and it will continue to turn until the detent extension 169 strikes a trip-pin 175 adjustably secured to the side frame. The continued movement of the handle to the full end of its stroke causes the toe 166 of the toggle actuator to be withdrawn from the detent, and immediately the spring 151 returns the main shaft and all of its connected parts to normal position. The release of the toe permits the toggle to resume its normal position, as shown in Fig. 16, the wiper riding up on the toggle link 173, and then as a spring 176 operates to return the handle to normal position, the wiper slides forward and drops into the position shown in Fig. 14, thereby permitting the spring 170 to automatically cause reengagement between the toe of the actuator and the detent. The trip 175 is so set that release of the main shaft from the actuating handle will not take place until such shaft has had its full movement imparted thereto. The position of the parts shown in Fig. 5, viewed from the exterior corresponds to the position of such parts shown in Fig. 16, viewed from the interior.

The lug 27 to which the card-receiver is attached slidably support a horizontally movable platen, shown on an enlarged scale in Figs. 20 and 21, and comprising a preferably metallic body 177, a yielding face 178 of rubber or other suitable material, attached to a flexible backing 179 which may be conveniently a strip of elastic metal, the backing in turn being fixedly connected with a series of rocking supports 180, two of the supports, as shown in Fig. 20, having attached pins or studs 181 which loosely enter sockets in the body and are retained in place by springs 182 fastened at one end to the body, and at the free ends to the studs. The supports 180 permit the different portions of the yielding face 178 to adapt themselves to the type, it being remembered that the timestamp is shifted transversely with relation to the card-receiver, so that the marking wheels will cooperate with different portions

of the platen face from day to day. Links 183 pivotally connected with the platen body are jointed at their outer ends to connected 5 rocking ears 184, fulcrumed at 185 on the top-plate 17 of the frame, an elongated arm 186 being extended rearwardly from and connected with the rocking ears and provided with a stud 187, see Fig. 10, which enters the bifurcated end of a link 188, the 10 lower end of the latter being pivotally connected with a bell-crank 189. A spring 190 is attached at one end to the link, and at the other end to the stud 187, so that there is a yielding connection between the said two 15 parts. A second link 191 connects the bell-crank with an arm 192 fast on the main shaft, so that when the latter is turned, it acts through the link 191 and the bell-crank to pull down the link 188, and through the 20 rocking ears 184 and the short links 183, the platen is moved rearward toward the marking wheels, the face of the platen passing through a slot 28* in the front wall of the card receiver. The platen face bears against 25 the back of the card, and when the limit of movement of the platen has been reached, the spring 190 then yields as the main shaft 131 completes its full movement, the spring allowing for variations in the thickness of the 30 cards, and also for a difference in the timing, so that the platen may be brought up to printing position before the full shaft-movement is effected.

A spring-controlled catch 193 on the arm 35 192 is adapted to engage with the hammer dog 194, and to lift and release the bell hammer 195 as the main shaft is turned, so that the bell or gong 196 will be struck to indicate the fact that the apparatus has been 40 operated.

A carriage shifting sheave 197 is fixedly secured to an upright spindle 198 having bearings in the base-plate 16 and on the cross-girt 19 respectively, said shaft having fast 45 thereon a gear 199, see Fig. 4, in mesh with a pinion 200, fast on a shaft 201 mounted on the base plate and having fast upon it a pinion 202 in turn meshing with another pinion 203 on an upright shaft 204, extended at its 50 upper end through the top-plate 17, and having attached to it a rotatable, visual day indicator 205. Said day indicator is shown slightly conical in shape, and having upon its periphery the days of the week, see Fig. 55 7, which day indications are brought one by one opposite an opening in a shield 206 on the top-plate, the shield opening coming opposite the aperture 3, as shown in Fig. 1. The spindle 198 is rotated intermittently by 60 means to be described, to cause the sheave 197 to wind upon it a chain or other flexible connection 207, which at its opposite ends is attached to the sheave and the time stamp carriage respectively, the sheave shifting the 65 carriage from right to left, viewing Fig. 1,

from day to day. A retracting sheave 208 is flexibly connected at 209 with the carriage, as by a chain, said sheave being fast on an upright shaft 210, supported in suitable bearings, one end of a retracting spring 211 being secured to the retracting sheave and attached at its lower end to an adjusting device shown as a ratchet wheel 212, Fig. 8, rotatable on the shaft and held in place by a detent 213. By moving the ratchet wheel 75 in one direction or the other, the tension of the retracting spring is increased or decreased, as may be necessary to secure the proper retractive action upon the carriage. It will be understood that as the connection 80 207 is wound onto the shifting sheave 197, the connection 209 will be unwound from the sheave 208, until at the end of the week the shifting sheave is released, as will be described, and thereupon the spring 211 acts 85 through the retracting sheave to wind up the connection 209, and pull the carriage back to initial position ready to start for the first day of the week. A buffer 214, Fig. 7, secured to the frame side, is arranged to engage 90 and stop the carriage when retracted as described. As the time movement or clock of a time recorder runs continuously I have provided for seven successive daily shifts of the carriage, thus including Sundays, the 95 retraction to initial position being effected at midnight Sunday.

A large disk gear 215 has its long hub loosely mounted on the shifting spindle 198, 100 said disk having in the present instance fourteen circularly arranged and equi-distant holes 216, Fig. 8, any one of which is adapted to receive a short pin 217 depending from a leaf-spring 218 fast on a plate 219 resting on the top of the disk and through which the 105 spindle 198 loosely passes. This plate has at its opposite ends two upturned and diametrically opposite stops 220 equi-distant from the center and adjacent the toothed periphery of the disk, one stop at a time 110 being engaged by the downturned end of a dog 221, Figs. 8 and 31, pivotally mounted on a radial arm 222 having its hub pinned to the shifting spindle 198 at 223, Fig. 31. A spring 224 normally maintains the dog in 115 operative position, a slot and pin connection 225, 226, Fig. 8, limiting the pivotal movement of the dog on its arm. By locking the stop-plate 219 to the disk 215 the dog acts to couple the disk and shifting spindle 198 120 together, the stress of the retracting spring 211 keeping the dog in engagement with one of the stops 220; the movement of the disk to shift the time stamp carriage being indicated by arrow 227, Fig. 8. Said disk 215 meshes with a smaller gear 228 loosely mounted on an upright post 229 fixed in the base plate 16, said gear having secured to it a let-off wheel 230, Figs. 8 and 29, with which co-operates a detent 231, forming one 125 130

arm of a bell-crank fulcrumed at 232, the other arm 233 of the bell-crank having a follower 234 which co-operates with the cam on the gear 50. By reference to Fig. 29 it will be seen that the greater portion of the cam is circular, as at 51^X, the irregular portion 51 of the cam being completed by a suitably shaped guard-plate 235 on gear 50. A large gear 236 loose on the post 229 below the gear 228 meshes with the pinion 49 fast on gear 50, so that the gear 236 is positively driven by the motor mechanism, whenever the latter is permitted to operate, which it will be remembered is at half-hourly intervals, the gear 50 making one complete revolution every twenty-four hours. The gears 228 and 236 constitute the members of a transmitting connection between the disk 215 and the motor mechanism, the latter directly driving the gear 236 while the member 228 and its attached let-off wheel 230 is spring-connected with the member 236 and actuated by a spring, as will be described. The gear 236 has a segmental slot 237, see dotted lines Fig. 29, into which projects a stud 238 depending from the gear 228, one end of a stiff bow-spring 239 being attached to the stud, the other end of the spring being secured to a pin 240 on the positively driven gear 236. While the detent 231 is operative the gear 228 and the disk 215 will be held locked from movement, the time stamp carriage remaining stationary, but the intermittent advances of the gear 236 will gradually increase the tension of the bow-spring 239 by bringing its ends toward each other, the stud 238 gradually approaching the advancing end of the slot 237, as in Fig. 29. In said figure the parts are shown in the position assumed just as the daily shift of the carriage is to be effected, viz: at midnight, and when that hour arrives the part 51 of the cam quickly throws outward the follower 234, rocking the bell-crank and withdrawing the detent 231 from the let-off wheel 230. The spring 239 is thereby released and it instantly expands, moving the gear 228 ahead a distance nearly equal to the length of the slot 237, and thereby the disk 215 is moved in the direction of arrow 227, Fig. 8, far enough to cause the shifting sheave 197 to pull or shift the carriage ahead, so that the time stamp will be in position to make records on the corresponding new day column of a card when placed in the receiver. The detent 231 is moved out and in by the cam, so that after releasing one tooth of the let-off 230 it is moved back into position to engage the next tooth and thereby lock the transmitting connection and the shifting means for the next twenty-four hours. As will be manifest the gradual compression of the spring 239 is effected during each twenty-four hour period and its quick release is effected at midnight of each day, in the mechanism herein illus-

trated, the daily shift of the time stamp being provided for automatically. The spring 239 which effects the daily shift is stronger than the carriage retracting spring 211, manifestly, as it acts against the latter to draw the carriage forward. As the disk 215 is advanced each day the dog 221 gradually approaches a trip 241 adjustably mounted on one of the upright posts 21 of the main frame, and when the last daily shift is made, at midnight Sunday, the trip engages the outer edge of the dog and pushes it inward, disengaging the depending end of said dog from the stop 220, such depending end being of less width than the dog, as clearly shown in Fig. 31. The shifting sheave and its spindle 198, and the dog-carrying arm 222, are thereby freed or uncoupled from the disk 215 and the retracting spring 211 operates, rotating the retracting sheave 208 and drawing the time stamp carriage back to initial position, shown in Fig. 3 for the Monday records. As the spindle 198 is reversely turned the arm 222 swings through an arc of 180° and the dog brings up against the other stop 220 of the pair, so that again the disk 215 and the shifting means are coupled together. By having a pair of stops 220 only one half a revolution of the shifting spindle is required when the carriage is retracted. The distance between two adjacent holes 216 in the disk represents one day, so that the entire series corresponds to two full weeks, it being seen that during one week one of the stops 220 is operative and during the next week the other stop is operative.

By lifting the finger-piece or leaf-spring 218 the lug or pin 217 is withdrawn from a hole in the disk and the stop-plate 219 can be angularly moved to any desired position on the disk, and thus serving through the dog 221 and its supporting arm, to vary the relative angularity of the disk and shifting sheave. Such manually operated device is provided to set the carriage at will and bring its position into correspondence with the day of the week on which it is desired to begin using the recorder, in a rapid and easy manner.

It now only remains to describe the means for controlling the feed, both longitudinal and transverse, of the ink-ribbon.

Two parallel upright and slotted guides 242, see Fig. 6, are rigidly secured to the cross-girth 19, Figs. 3, 4 and 7, and blocks 243, connected rigidly by a cross-bar 244, are adapted to slide vertically on the guides and constitute a ribbon-carriage, each block having a vertical tongue 243^X, Figs. 34 and 35, to enter the slotted guides. A shaft 245 is rotatably mounted in bearings in the lower ends of the blocks, cams 246 being attached to the ends of the shaft and resting upon the horizontal lugs 20 of the frame sides, gears 130

247 fast on the shaft outside of the slide-blocks being adapted to mesh with pinions 248 on upright spindles 249 mounted one on each block of the ribbon-carriage, a ribbon-spool 250 being secured to the upper end of each spindle. The shaft 245 is capable of slight longitudinal movement sufficient to bring one of the gears 247 into engagement with its adjacent pinion 248 and simultaneously to release the other gear from its pinion, such movement of the shaft providing for a reversal in the direction of longitudinal feed of the ink-ribbon 251, wound upon the spools. When winding upon one spool the ribbon unwinds from the other spool, the latter at that time being disconnected from the shaft 245, the ribbon passing across the opening 30^x in the card receiver, and in front of the marking wheels H and M of the time stamp. A ratchet 252 on the shaft 245 is advanced each time the apparatus is operated, by or through the pawls 253 on a pawl-carrier 254, see Fig. 19, actuated by a link 255 operatively connected with the arm 152 of the main shaft 131. Thus the longitudinal feed of the ribbon is effected intermittently, in either direction, and as the cams 246 rotate they alternately raise and lower the ribbon-carriage, imparting a cross-feed to the ink-ribbon, thereby causing the entire surface thereof to be used, and greatly increasing the useful life of the ribbon. To automatically reverse the longitudinal feed I have fulcrumed on depending extensions 256 of the cross-bar 244, see Figs. 34 and 35, two upright arms 257 bifurcated at their upper ends to receive the ribbon, said arms being connected by a link 258, provided with yoke-pins 259, Figs. 3 and 7, 34 and 35, to engage a shifting toggle 260, 261, mounted on the ribbon-carriage, see Fig. 3, the center joint of said toggle playing between two collars 262 on the shaft 245. A pin 261^x on the lower end of the toggle-arm 261 extends through a vertical slot 256^x in the adjacent extension 256, and one end of a spring 300, Fig. 35, is attached to the pin, the other end of the spring being secured to the uplifted end of the extension, the spring acting to throw over the toggle after it has been pushed past dead center in either direction, the spring normally being in tension. As the toggle is straightened the spring is stretched, and as soon as dead center is passed the spring contracts, shifting the shaft 245 by the engagement of the center joint of the toggle with one or the other collar 262, so that one gear 247 is withdrawn from its pinion 248 and the other gear 247 is moved into mesh with its pinion. A holding block 270 on the free end of a leaf-spring 271, Figs. 7 and 34, attached to the cross-bar 244, is held by the spring against one side of a double-beveled collar 272 fast on the shaft 245, and acting to keep one gear 247 and its pinion 248 in mesh until the toggle is pushed past dead center. The spring 300 is sufficiently powerful to snap the holding block 270 from one to the other beveled face of the collar when the toggle is thrown by the spring. By making any suitable enlargement or obstruction on the ribbon, as by pinning a fold 263 thereon, see Fig. 3, near the ribbon ends, the arms 257 are swung from one to the other position to operate the toggle and shift the shaft 245 longitudinally, 70 to thereby reverse the direction of longitudinal feed. In Fig. 3 the fold 263 is approaching the right-hand arm 257 and when it engages the same will swing it to the left, throwing over the toggle and thereby moving the shaft 245 to the left, disengaging its gear 247 from the pinion 248 on the left-hand spool-spindle, and bringing the right-hand gear into mesh with its gear. The ribbon feed will thereafter be from left to right, until a similar obstruction or fold near the left-hand end of the ribbon engages and swings the left-hand arm 257 to the right. The specific means for reversing the feed may be modified or varied in different mechanical 80 particulars without departing from the spirit and scope of my invention.

In the structure hereinbefore described the series of stops, coöperating with the card receiver to change the vertical position of a card therein, are mounted on radial arms helically arranged on a rotatable carrier,—with the exception of the 8 p. m. to midnight stop—but if desired all of the stops can be similarly arranged, to be operatively positioned by coöperation one after another with a series of arms arranged on a revolving carrier. Such modification is illustrated in Figs. 25 and 26, the series of stops 264 being supported on swinging plates 265 fulcrumed on lugs 266 projecting from the front wall of the card receiver, each stop and its supporting plate corresponding substantially to the stop 42 and its plate 41 shown in Fig. 23. The rotatable shaft 35 would then be provided with a helically arranged series of radial arms 267, each coöperating with its particular stop-plate 265 at the proper time to move the corresponding stop 264 into the opening 29 of the card receiver, and one of the arms, at the upper end of shaft 35, would be shaped similarly to the cam-arm 39, Fig. 23, to operate in like manner.

The operation of the various parts of the apparatus having already been described in detail, it only remains to briefly refer to the manner in which the time recorder is used.

The workman, whether entering or leaving his place of employment, deposits his card in the card receiver, with the back of the card toward him, and then grasps the actuating handle and pulls it forward its full stroke. The time is thereby recorded on the card, at the proper place thereon, the record giving the day, hour and minute, and 130

- the mechanism is automatically released from the actuating handle as its full stroke is made, the workman then withdrawing his card and passing on. No difference is made 5 in the mode of operation whether it is an "in" or an "out" record, as will be manifest, the workman being required to insert the card, pull the handle over, and remove the card, the apparatus itself showing by the 10 record whether the workman was coming to work or leaving it. Thus no power of selection is left to the operator as to whether some part shall or shall not be moved in or out, to the left or right, etc.
- 15 Changes or modifications may be made by those skilled in the art in various details of construction and arrangement without departing from the spirit and scope of my invention, one practical embodiment where- 20 of is herein shown and described in detail.
- Having described my invention, what I claim as new and desire to secure by Letters Patent, is:—
1. The combination with a manually- 25 actuated time stamp, of a fixed card receiver or guide, a series of successively coöperating stops to vary the position of a card in said receiver relatively to the time stamp, means to effect the movement of the stops one 30 after another into operative position at predetermined intervals of time, and means to change the position of the time stamp relatively to the card receiver at greater intervals.
  - 35 2. The combination with a time stamp, and a card receiver or guide, of a plurality of stops to coöperate individually with the receiver and vary the position of a card therein relatively to the time stamp, means 40 to effect positioning of the stops one by one at predetermined intervals of time, and automatic means operating at greater intervals to effect a change in the relative position of the time stamp and card receiver.
  - 45 3. The combination with a time stamp, of an upright card receiver or guide, having a vertical opening therein, a series of stops located in parallel planes one above the other, and means to cause the entire series 50 of said stops to move in succession each day into the opening in the card receiver at predetermined intervals of time, to thereby correspondingly change the relative position of the time stamp and a card inserted in the 55 receiver, and other means to change the relative position of the time stamp and a card from day to day.
  - 60 4. The combination, with a time stamp, of a receiver or guide adjacent thereto and into which a card is inserted to be stamped, said receiver having a longitudinal opening in one of its walls, a rotatable carrier adjacent and parallel to such opening, a series of radially extended arms helically disposed 65 thereon in parallel planes, a spring-con-
- trolled stop pivotally mounted on the end of each arm, and means to rotate the carrier step by step at predetermined intervals of time, to thereby move each stop into the receiver opening, one after another, each 70 stop snapping into position as it clears one side of the opening in the receiver.
5. In a time recorder, in combination, a time stamp, an upright card receiver or guide adjacent thereto and having an elongated opening in one of its walls, a series of stops arranged one above the other in a helix and disposed in parallel planes, means to bodily rotate said series step by step to thereby bring one after another of the stops 75 into operative position in the opening of the receiver, to reduce the effective depth thereof at predetermined intervals of time, and yielding means to permit the movement of each stop into and out of operative position 80 in the opening.
6. The combination, with a time stamp, of an adjacent upright card receiver having a stamping opening, a series of stops, a rotatable carrier on which said stops are yield- 85 90 ingly mounted in helical arrangement and in parallel horizontal planes, mechanism to intermittently rotate the carrier to bring one after another of said stops, beginning with the lowest, into position to sustain a card 95 in the receiver, whereby different portions of the card will be presented at the stamping opening, means to automatically aline the card so that the positions due to one complete operation of the entire series of stops 100 will be in a single vertical column on the card, and a time movement to permit the carrier-actuating mechanism to operate at predetermined periods of time.
7. In a time recorder, in combination, a 105 time stamp, means to govern the position of a card relatively thereto so that successive time records for a given day will be located in a single longitudinal column on the card, separate means to effect a lateral change in 110 the relative position of the card and time stamp at the beginning of each day, whereby the records of one day can be made only in the column for that day and cannot interfere with those of the next, and means to effect 115 column alinement of the card each time a record is made thereon.
8. In a time recorder, in combination, a 120 time stamp, means to change the vertical position of a card relatively thereto at pre- 125 determined intervals, whereby successive time records for a given day will lie in a vertical column on the card and can be made only in the column for that day, separate means to effect a lateral change in the relative position of the card and stamp at the beginning of each day, to positively prevent interference of the records of one day with those of the next, and a visual indicator to show the daily change.

9. The combination, with a time stamp, of an upright card receiver, a rotatable carrier adjacent thereto, a series of yieldingly mounted, helically disposed stops on the carrier, to successively coöperate with and gradually decrease the effective depth of the receiver, means to operate the carrier at predetermined intervals of time, and a time indicator movable with the carrier, to facilitate setting thereof. 10. The combination, with a time stamp, of an upright card receiver, a rotatable carrier adjacent thereto, a series of yieldingly mounted, helically disposed stops on the carrier, to successively coöperate with and gradually decrease the effective depth of the receiver, motive mechanism controlled by a time movement to effect rotation of the carrier at equal intervals of time, and a time indicator mounted on the carrier to facilitate setting of the same. 11. The combination, with a time stamp, of an upright card receiver, a rotatable carrier adjacent thereto, a series of yieldingly mounted, helically disposed stops on the carrier, to successively coöperate with and gradually decrease the effective depth of the receiver, motive mechanism controlled by a time movement to effect rotation of the carrier at equal intervals of time, and an indicator rotatable in unison with the carrier and having a time scale divided into intervals corresponding to the rotative periods of the carrier, whereby setting of the latter is facilitated and simplified. 12. The combination, with a time stamp, of an upright card receiver, a rotatable carrier adjacent thereto, a series of yieldingly mounted, helically disposed stops on the carrier, to successively coöperate with and gradually decrease the effective depth of the receiver, means to operate the carrier at predetermined equal intervals of time, a time indicator rotatable in unison with the carrier, to facilitate setting thereof, means to effect a daily shift or change in the relative position of the time stamp and card receiver, and a visual indicator to show the daily change. 13. In a time recorder, in combination, a time stamp, an adjacent receiver for the card when stamped, a series of stops to successively coöperate with the receiver and gradually decrease its depth at stated intervals from a predetermined morning hour to a predetermined evening hour, means to effect automatically the operative positioning of said series of stops, a separate stop, and means to maintain it continuously in operative position relatively to the receiver from such evening hour till midnight. 14. The combination with a time stamp, and manually controlled means to effect its actuation, of a fixed card receiver or guide having a fixed wall, and means to automatically press one edge of the card against said wall by the actuation of the time stamp to align the card in record-receiving position. 15. In a time recorder, the combination, with a card receiver, and means to gradually change the effective depth thereof, such changes being effected at predetermined, equal intervals of time, of a time stamp including hour and minute marking members, means to advance the former member at the end of each hour, and means to cause the latter member to record a minute in one subdivision of the hour at a different point on the card, relatively to the hour record, from that at which a minute in another subdivision will be recorded. 16. In a time recorder, the combination, with a card receiver, and means to change the depth thereof by an equal amount at the end of half hour periods, of a time stamp including hour and minute marking wheels, the latter having minute-indications thereon, divided into a number of groups, means to advance the hour marking wheel at the end of each hour, and a time movement to actuate the minute marking wheel, the grouping of the minute-indications causing the recording of an indication in each of two successive groups in different positions with relation to the hour indication. 17. In a time recorder, an upright card receiver, a series of stops successively coöperating therewith to gradually decrease its effective depth, motor mechanism controlled by a time movement to operate the stops and change the depth of the receiver at half-hour intervals, a time stamp, including hour and minute marking members, connections between said motor mechanism and the former of said members to advance such member at the end of each hour, minute-indications on the minute-marking member, divided into four groups, and means to actuate the said member, the grouping of the indications thereon causing a minute-indication in the first and third group to be recorded on the card adjacent one half of the hour record, and in the second and fourth groups adjacent the other half of the hour record. 18. In a time recorder, a time stamp, including hour and minute marking wheels, twenty-four hour-indications on the former, sixty minute-indications on the latter, divided into four groups of fifteen each, means to sustain a card in position to receive a record by operation of the time stamp, and mechanism to effect the operation of the marking wheels, the grouping of the minute-indications causing a change in the position of the minute record relative to the hour record every fifteen minutes. 19. The combination, in a time recorder, of a time movement, a time stamp, including hour and minute type-wheels, a motor mechanism operatively connected with the hour

wheel, an escapement for said mechanism, controlled by the time movement, to cause advance of the hour wheel at hourly intervals, a connection between the time movement and the minute wheel, to normally advance the latter, and means to automatically and positively lock said wheels together only when the time stamp is operated.

20. The combination, in a time recorder, of a time movement, a time stamp, including hour and minute type-wheels, a motor mechanism, reducing or lost-motion gearing between said mechanism and the hour wheel, an escapement for said mechanism controlled by the time movement and permitting the mechanism to operate half-hourly, the reducing gearing causing hourly advance of the hour wheel, a connection between the time movement and the minute wheel, to operate the latter, said connection including a yielding coupling, to permit temporary stoppage of the minute wheel, and means to center and lock together the hour and minute wheels upon operation of the time stamp.

25. 21. The combination, in a time recorder, of a time movement, a time stamp, including hour and minute type-wheels, a motor mechanism, a lost-motion connection between it and the hour wheel, card positioning means, intermittently actuated by said motor mechanism, means controlled by the time movement to permit the operation of said mechanism at predetermined intervals, the lost-motion connection causing hourly change of 30 the hour wheel, a connection between the time movement and the minute wheel, to operate the latter, and means to center and lock the type wheels by or through operation of the time stamp.

40 22. The combination, with hour and minute marking wheels, having minute indications on the latter spaced into groups, of means to center the wheels for marking their combined record, the spacing of the minute-indications causing indications in adjacent groups to be positioned differently with relation to a given hour-indication when the marking wheels are centered.

23. The combination, with hour and minute marking wheels, the latter having minute-indications thereon spaced into groups, of a time movement to actuate the minute wheel and control the actuation of the hour wheel, and means to lock and center the 55 wheels for making their combined record, the spacing of the minute-indications causing indications in adjacent groups to be positioned differently with relation to a given hour-indication when the marking wheels are centered.

60 24. The combination, with hour and minute marking wheels, each having an attached centering ratchet, of a time movement to directly actuate the minute wheel, a motor mechanism controlled by said time move-

ment, to intermittently actuate the hour 65 wheel, means to operate the wheels to make a combined record, and pawls automatically actuated by said record making means to simultaneously coöperate with the ratchets and lock together and center the marking 70 wheels when the record is made.

25. The combination, with hour and minute marking wheels, each having an attached centering ratchet, and means to actuate them by or through a time movement, of 75 manually-actuated means to operate the marking wheels to make a record, two connected pawls to coöperate respectively with the separate centering ratchets upon recording operation of the wheels, and means to 80 change the direction of motion of the pawl of the minute-wheel ratchet if it catches upon the point of a tooth thereof, to insure the centering of the said minute wheel.

26. The combination with a carriage, hour 85 and minute marking wheels thereon actuated by or through a time movement, and a centering ratchet attached to each wheel, of manually-actuated means to move the carriage and thereby cause a record to be made 90 by the marking wheels, a rock-shaft on the carriage, a pawl fast thereon to coöperate with the hour-wheel ratchet, a second pawl to coöperate with the minute-wheel ratchet, a yielding, eccentric connection between said 95 pawl and the rock-shaft, to change the direction of motion of the pawl if it catches on the point of a tooth of its ratchet, and means to automatically rock said shaft and effect co-operation between the pawls and ratchets to 100 center and lock the type wheels upon the operation of the carriage-moving means.

27. In a time recorder, in combination, a time stamp, including hour and minute marking members, a carriage on which they 105 are mounted, and a platen; and means to first automatically lock said marking members together and thereafter to move the carriage to the printing point and thereafter position the platen to cause an impression to be 110 marked on a card held between the marking members and the platen.

28. In a time recorder, in combination, a time stamp, including hour and minute marking members, a carriage on which they 115 are mounted, and a platen; a card receiver to support a card between said marking members and the platen, means to move the carriage toward the card and thereafter effect movement of the platen to cause a record to 120 be stamped on the card, and means to adjust the position of the carriage relatively to the card receiver when the carriage is moved to the printing point.

29. The combination, with hour and minute marking wheels of a time stamp, of a platen to coöperate therewith, having a yielding face, and a plurality of rocking sup-

ports connecting the face and the platen and permitting the face to accommodate itself to the pressure.

30. The combination, with hour and minute marking wheels of a time stamp, of a platen to coöperate therewith, and consisting of a body, a yielding face-member, a plurality of supports attached thereto and adapted to rock on the body, and means to retain the supports in position on the body.

31. The combination, with hour and minute marking wheels of a time stamp, of a pressure platen to coöperate therewith, consisting of a body, a yielding face having an attached flexible backing, a series of supports fixedly connected with the backing and adapted to rock on the body, and spring-controlled means to retain the facing and attached parts in position on the body.

32. In a time recorder, a time stamp including hour and minute marking members, and a platen, combined with manually-controlled stamp-operating means to move the marking members and platen toward each other, to make a record, and a device to automatically release the time stamp from control of its operating means when the latter has been actuated and after the stamp has been operated.

33. In a time recorder, in combination, a time stamp, a carriage on which it is mounted, a main operating shaft, positive connections between it and the carriage to swing the latter and effect the operation of the stamp when the shaft is turned, a handle to turn the shaft and thereby cause the carriage to be swung, a device to disconnect the shaft and handle automatically at the end of the operative movement of the handle, thereby releasing the carriage and time stamp after the latter has been operated and means to thereupon return the carriage to normal position.

34. In a time recorder, in combination, a time stamp, a carriage on which it is mounted, a main operating shaft, connections, including a cam and follower, between the shaft and carriage, to positively move the latter and cause the time stamp to make a record, a spring to return the parts to normal position, an actuating handle, a coupling between it and the said shaft, and means to automatically uncouple the shaft and handle when operative movement of the latter has been effected and after the record has been made.

35. In a time recorder, in combination, a time stamp, a rock-shaft operatively connected therewith, a handle loosely mounted on the shaft, a toggle-actuator carried by the handle, a toggle to turn the rock-shaft when engaged by said actuator, the shaft and handle being thereby coupled to move in unison, a detent for and to normally retain the actuator in operative condition, and a release or trip to disengage automatically the

detent from and thereby free the toggle-actuator when the handle reaches a predetermined point in its actuating stroke.

36. In a time recorder, in combination, a carriage, a time stamp thereon including hour and minute marking wheels each having an attached centering ratchet, and connected pawls to coöperate therewith, a main operating shaft, connections between it and the carriage to move the latter and thereby bring the marking wheels to recording position, a yielding connection between the shaft and the centering pawls, to bring the latter into coöperation with the ratchets upon initial movement of the shaft, a handle to actuate the latter, and means to release the shaft from control of the handle when the proper movement of the shaft has been effected.

37. In a time recorder, a time stamp, a swinging carriage on which it is mounted, an actuating handle, connections between it and the carriage to swing the latter and operatively position the time stamp, a retracting spring for said connections, means to automatically release said connections from the actuating handle when the latter has completed its operative stroke, and a damping or cushioning device to take up the jar when the carriage is thus free to return to normal position.

38. The combination, with a time stamp including hour and minute type-wheels, of a ribbon-carriage, an ink-ribbon, spools mounted on the carriage to sustain the ribbon, means to feed the ribbon longitudinally from one to the other spool, and automatically-rotated cams to support the carriage and by which the latter is traversed transversely to the longitudinal feed of the ribbon.

39. In a time recorder, in combination, a card receiver, a time stamp, actuating means to cause it to mark a card in the receiver, mechanism to effect a periodic shift of the time stamp with relation to the card receiver, and automatic means to effect return of the time stamp to initial position and restore it automatically to the control of said shifting mechanism after a predetermined number of periodic shifts.

40. In a time recorder, in combination, a card receiver, a time stamp, a motor mechanism, connections between it and the time stamp to effect a periodic shift of the stamp relatively to the card receiver, and separate means controlled wholly by the motor mechanism to automatically effect return of the time stamp to initial position after a predetermined number of periodic shifts, and place said time stamp again under the control of the motor mechanism.

41. In a time recorder, in combination, a card receiver, a time stamp, a motor mechanism operatively connected with the time stamp, an escapement coöoperating with said mechanism to effect intermittently a periodic

shift in the position of the time stamp, a visual indicator for the periodic shifts, and automatic means to return the time stamp to initial position when a predetermined number of periodic shifts have been made and place the time stamp again under the control of the motor mechanism.

42. In a time recorder, a fixed card receiver, a time stamp, movable transversely thereto, actuating means to cause the stamp to mark a card in the receiver, mechanism to effect a periodic shift of the time stamp relatively to the card receiver, spring-actuated means to retract the time stamp to initial or starting position, and means to automatically release the time stamp from control of the shifting mechanism when a predetermined number of periodic shifts have been made, to permit the retracting means to effect initial positioning of the time stamp, the operation of the shifting mechanism placing the said spring-actuated means in condition to subsequently retract the time stamp.

43. In a time recorder, a card receiver, a time stamp including hour and minute marking wheels, a time movement to actuate the latter, a shiftable carriage on which the time stamp is mounted, a motor mechanism operatively connected with the hour marking wheel, an escapement controlled by the time movement to permit hourly advances of the hour wheel by said mechanism, means to shift the carriage relatively to the card receiver when the hour wheel has made a predetermined number of advances, to thereby cause a periodic change in the position of the time stamp, and automatic means to return the carriage to initial or starting position and restore it automatically to the control of the shifting means at the end of a given number of periodic changes.

44. In a time recorder, a fixed card receiver, a time stamp movable transversely thereto, actuating means to cause the stamp to mark a card in the receiver, mechanism to effect a periodic shift of the time stamp relatively to the card receiver, spring-actuated means to retract the time stamp to initial or starting position, a device to adjust the tension of the actuating spring thereof, a visual indicator to indicate the periodic shift of the time stamp, and means to temporarily release the latter from control of the shifting mechanism after a given number of periodic shifts, to permit the retracting means to effect initial positioning of the time stamp.

45. In a time recorder, in combination, a card receiver, a time stamp, actuating means to cause it to mark a card in the receiver, mechanism to effect a periodic shift of the time stamp with relation to the card receiver, and automatic means to effect return of the time stamp to initial position after a predetermined number of periodic shifts, said shifting means including a manually-operated

device whereby the time stamp can be shifted forward or back by hand to any point in its path of movement.

46. In a time recorder, in combination, a card receiver, a time stamp, actuating means to cause it to mark a card in the receiver, mechanism to effect a periodic shift of the time stamp with relation to the card receiver, a visual indicator marked to indicate the periodic shifts, and automatic means to return the time stamp to initial position at the end of a given number of shifts, said shifting means including a manually-operated device to set the time stamp forward or back by hand, the indicator indicating the corresponding change or shift of the time stamp.

47. In a time recorder, in combination, a time stamp, a carriage on which it is mounted, a fixed card receiver, means to shift the carriage periodically with relation to the card receiver, actuating means to cause the stamp to mark a card in the receiver, means to gradually decrease the depth of the latter at stated intervals, whereby the card will be changed as to its marking position in the direction of its length, the shifting of the carriage causing records made by the stamp during different periods to appear in different longitudinal columns on the card, and automatic means to effect return of the carriage to initial position at the end of a given number of shifts.

48. In a time recorder, in combination, a time stamp, a shifting carriage therefor, a card receiver transversely to which the carriage is movable, a spring-actuated retracting sheave, a shifting sheave, flexible connections between the carriage and said sheave, a rotatable disk, a motor mechanism connected with and to effect intermittent rotative movement of the disk at the end of each day, means normally connecting the disk and shifting sheave, to effect daily shift of the carriage by movement of the disk, and a device to render said means inoperative and thereby disconnect the said disk and sheave, when the disk has effected a predetermined number of daily shifts of the carriage, the retracting sheave thereupon effecting automatic return of the carriage to initial position.

49. In a time recorder, in combination, a time stamp, a shifting carriage therefor, a card receiver transversely to which the carriage is movable, a spring to retract the carriage to initial position, a shifting sheave, a flexible connection between it and the carriage, to move the latter in opposition to the spring, a disk co-axial with the sheave, means to normally cause unison rotation of said sheave and disk, a trip to automatically render said means inoperative when the disk has been given a predetermined angular movement, whereby the retracting spring can return the carriage to initial position, a

manually-operated device to vary the relative angularity of the sheave and disk to set the carriage at will, and motor mechanism to intermittently rotate the disk at intervals, whereby a periodic shift of the carriage is effected, the disconnection of the shifting sheave and disk taking place when a definite number of periodic shifts have been made.

50. In a time recorder, in combination, a time stamp, a shifting carriage therefor, a card receiver transversely to which the carriage is movable, a spring to retract the carriage to initial position, a shifting sheave, a flexible connection between it and the carriage, to move the latter in opposition to the spring a disk co-axial with the sheave, a manually-adjustable stop on the disk, a dog movable with the sheave and normally in engagement with the stop, to effect rotation 10 of the sheave by rotation of the disk, a trip to disengage the dog and stop and thereby free the sheave when the disk has been given a predetermined angular movement, to permit retraction of the carriage, and motor mechanism controlled by a time movement 15 and operatively connected with the disk, to effect angular advance thereof at the end of given periods and thereby cause periodic shifting of the carriage.

51. In a time recorder, in combination, a time stamp, a shifting carriage therefor, a card receiver transversely to which the carriage is movable, a spring to retract the carriage to initial position, a shifting sheave, a flexible connection between it and the carriage, to move the latter in opposition to the spring, a disk coaxial with the sheave, a manually-adjustable stop on the disk, a dog movable with the sheave and normally in engagement with the stop, to effect rotation of the sheave by rotation of the disk, a trip to disengage the dog and stop and thereby free the sheave when the disk has been given a predetermined angular movement, to permit 20 retraction of the carriage, motor mechanism controlled by a time movement, and a transmitting connection between said mechanism and the disk, said connection including a member directly driven by the motor mechanism, a spring-connected let-off member 25 geared to the disk, and an intermittently-operative detent for the let-off member, release of the latter by the detent acting to advance the disk one step and therethrough 30 shift the carriage forward.

52. In apparatus of the class described, a time stamp, a carriage therefor, a spring to retract it, a shifting sheave and a flexible connection between it and the carriage to move the latter in opposition to the spring, a disk loose on the sheave spindle, a coupling device to normally connect the disk and spindle, a let-off member geared to the disk, a gear concentric with said member, a slot 35 and pin connection between them, a spring

attached at its ends to said gear and let-off member, respectively, rotation of the gear compressing the spring as the pin travels in the slot, a motor mechanism to drive the gear and controlled by a time movement, a cam operated by said mechanism, a detent for said let-off member governed by the cam, and means to automatically uncouple the shifting sheave and disk at the end of each week, the cam causing the detent to release 75 the let-off member at the end of each day, whereby the expansion of the connected spring turns said member and through the disk and sheave shifts the carriage ahead one step, thus effecting a daily shift of the said 80 carriage, the detent being automatically returned to operative position by the cam after each release of the let-off member, to provide for compression of its actuating spring by the motor-driven gear.

53. In a time recorder, a time stamp, and operating devices therefor, combined with a fixed card receiver, a series of stops to act individually upon and thereby limit the movement of a card relatively to the time stamp when inserted in the receiver, mechanism controlled by a time movement to operate said stops, and automatic means to yieldingly engage and laterally position the card in the receiver.

54. In a time recorder, in combination, a time stamp including separately driven hour and minute marking wheels, a time movement, a motor mechanism controlled thereby and operatively connected with the hour wheel, to intermittently actuate it, a revolving driver actuated by the time movement in an annular path adjacent the minute wheel, and yielding abutments mounted on the latter and co-operating oppositely with the driver, normal movement of the latter effecting the operation of the minute wheel in unison with the time movement, temporary variation in the movement of the wheel causing one of the abutments to yield as the driver advances, to thereby prevent stoppage or disarrangement of the time movement.

55. In a time recorder, in combination, a time stamp including separately driven hour and minute marking wheels, a time movement, a motor mechanism controlled thereby, operatively connected with and to intermittently actuate the hour wheel, a driving member operatively connected with the time 110 movement and continuously driven thereby, and spring-controlled abutments on the minute wheel and oppositely engaging said driving member, to normally cause rotation of the wheel therewith, yielding of an abutment when the movement of the minute wheel is temporarily varied permitting lost motion between it and the time movement, to prevent disarrangement thereof, the opposing action of the abutments upon the 115 120 125 130

driving member serving, when the minute wheel is released, to accurately set the same with relation to the driving member.

56. In a time recorder, in combination, a time stamp including hour and minute marking wheels, a time movement, a yielding, self-setting connection between it and the minute wheel, to drive the latter while permitting temporary variation in the movement thereof while the time movement continues to operate, a motor mechanism to intermittently actuate the hour wheel, a card receiver, means to cause the marking wheels to stamp a record upon a card in the receiver, and a device to lock the marking wheels together and from rotative movement upon the operation of such means.

57. In a time recorder, in combination, a time stamp including hour and minute marking wheels, a time movement, a yielding, self-setting connection between it and the minute wheel, to drive the latter while permitting temporary variation in the movement thereof while the time movement continues to operate, a motor mechanism to intermittently actuate the hour wheel, a card receiver, means to cause the marking wheels to stamp a record upon a card in the receiver, and mechanism to center the marking wheels when a record is made thereby.

58. In a time recorder, in combination, a time stamp, including hour and minute marking wheels, a motor mechanism operatively connected with the hour wheel, an escapement, including worm let-off, for and to cause intermittent operation of said mechanism, a time movement, and connections between it and the worm let-off and minute wheel, respectively, to operate the same.

- 40 59. In a time recorder, in combination, a time stamp, including hour and minute marking wheels, a motor mechanism operatively connected with the hour wheel, an escapement for and to cause intermittent operation of said mechanism, the escapement including a star-wheel and a coöperating worm let-off having a steep pitch, a time movement operatively connected with and to actuate the minute wheel, and a connection between the time movement and worm let-off, to govern rotation of the latter.

- 60 60. In a time recorder, in combination, a time stamp, including hour and minute marking wheels, a motor mechanism operatively connected with the hour wheel, an escapement for and to cause intermittent operation of said mechanism, the escapement including a star-wheel and a coöperating worm let-off having a steep pitch, a time movement operatively connected with and to actuate the minute wheel, a connection between the time movement and worm let-off, to govern rotation of the latter, a card receiver adjacent the time stamp, a series of stops to successively coöperate with and

vary the effective depth of the receiver, and actuating connections between said stops and the motor mechanism, to intermittently move and operatively position the stops one by one.

- 70 61. In a time recorder, in combination, a time stamp, including hour and minute marking wheels, a motor mechanism operatively connected with the hour wheel, an escapement for the motor mechanism, including a worm let-off and a rotatable spindle on which it is mounted, a time movement operatively connected with and to actuate the minute wheel, and a separate connection between said time movement and spindle, said connection including a manually-released coupling whereby the escapement can be set by hand in accord with the time movement.

- 75 62. In a time recorder, in combination, a time stamp, including hour and minute marking wheels, a motor mechanism operatively connected with the hour wheel, an escapement for the motor mechanism, including a worm let-off and a rotatable spindle on which it is mounted, a time movement operatively connected with and to actuate the minute wheel, and a separate connection between said time movement and spindle, said connection including a manually-released coupling whereby the escapement can be set by hand in accord with the time movement, and graduated adjusting means whereby when the escapement is roughly set by the coupling the final, exact adjustment can be made by said adjusting means.

- 90 63. In a time recorder, in combination, a time stamp including hour and minute marking wheels, the latter operated by a time movement, a motor mechanism operatively connected with and to intermittently actuate the hour wheel, an escapement to cause such intermittent operation of said mechanism, said escapement including a let-off member and a rotatable spindle on which it is mounted, a time movement, a shaft rotated thereby, a graduated disk fast on the spindle, a second graduated disk loose on the shaft, adjustable means to clamp the disks together, and a manually-released coupling between the second disk and the shaft, said disks and coupling providing for setting and accurate adjustment of the escapement with relation to the time movement.

- 105 64. In a time recorder, in combination, a time stamp including hour and minute marking wheels, the latter operated by a time movement, a motor mechanism operatively connected with and to intermittently actuate the hour wheel, an escapement to cause such intermittent operation of said mechanism, a time movement, a shaft rotated thereby, a rotatable transmitting spindle between the shaft and escapement, and a manually-released coupling and adjustable setting device connecting said shaft and spindle.

65. In a time recorder, in combination, a card receiver, hour and minute marking wheels, means to cause them to stamp a card in the receiver, a time movement to actuate the minute wheel, mechanism to change the hour wheel at the end of each hour, means to lock the minute wheel at the fifty-ninth minute of each hour to prevent a completed hour record prior to change of the hour wheel, and means operative upon such change to again lock the minute wheel and prevent recording of the fifty-ninth minute at the beginning of the new hour.

66. In a time recorder, in combination, a card receiver, hour and minute marking wheels, actuating means to cause them to stamp a card in the receiver, a time movement to actuate the minute wheel, mechanism to change the hour wheel at the end of each hour, and means to automatically insure change of the minute wheel from 59 to 0 at the change of the hour and prevent the printing of 0 before such change of hour.

67. The combination, with a minute wheel, and a time movement to actuate it, of an hour wheel, mechanism controlled by said time movement to advance the hour wheel at the end of each hour, means to coöperate with the minute wheel prior to such advance of the hour wheel, to prevent the record of the hour and no minutes, and means coöperating with the minute wheel immediately after advance of the hour wheel to prevent the record of the new hour and fifty-nine minutes.

68. The combination, with a minute wheel, and a time movement to actuate it, of an hour wheel, mechanism, controlled by said time movement to advance the hour wheel at the end of each hour, a stop operatively positioned by each advance of the hour wheel, and two pawls rotatable with the minute wheel, one pawl coöoperating with the stop and locking said minute wheel at the end of the hour, to prevent record of the hour and no minutes, the change of the hour wheel releasing said pawl and bringing the other pawl into coöperation with the stop, to prevent record of the new hour and fifty-nine minutes.

69. The combination, with a minute wheel, and a time movement to actuate it, of an hour wheel, mechanism controlled by said time movement to advance the hour wheel at the end of each hour, a toothed stop rotated step by step in unison with the hour wheel, a spring-controlled pawl movable with the minute wheel and brought into coöperation with a tooth of the stop at the end of the hour, to lock the minute wheel and prevent record of the hour and no minutes, rotation of the stop at the change of hour by the hour wheel releasing said pawl, its spring clearing it from the stop, and a second pawl movable

with the minute wheel and adapted to engage the freshly positioned tooth of the stop upon change of hour, to lock the minute wheel and prevent record of the new hour and fifty-nine minutes.

70. The combination, with a minute wheel, and a time movement to actuate it, of an hour wheel, mechanism controlled by said time movement to advance the hour wheel at the end of each hour, a toothed stop rotated step by step in unison with the hour wheel, a swinging, spring-controlled pawl movable bodily with the minute wheel and having a limited movement relative thereto, rotation of the said wheel bringing said pawl into locking engagement with a tooth of the stop just before change of the hour, to lock the minute wheel until the hour change is effected, such change rotating the stop and releasing the pawl, and a second pawl movable with the minute wheel and adapted to engage or ride over and drop behind the freshly positioned tooth of the stop upon change of the hour, to lock the minute wheel from retrograde movement, such double locking of the minute wheel insuring change of the minute wheel from 59 to 0 at the change of the hour.

71. The combination, with a minute wheel, and a time movement to actuate it, of an hour wheel, mechanism controlled by said time movement to advance the hour wheel at the end of each hour, a rotatable toothed stop operatively positioned by each advance of the hour wheel, and means rotatable with the minute wheel and coöperating with the stop wheel, to lock said minute wheel at the end of the hour and thereby prevent record of the hour and no minutes, movement of the toothed stop by advance of the hour wheel at the change of the hour causing said means and the stop to again coöperate and prevent record of the new hour and fifty-nine minutes.

72. In a time recorder, printing mechanism, a card guide or receiver, a plurality of rotatable yieldingly mounted stops, and means to rotate said stops to progressively and successively project the same into the guide or receiver to limit the movement of a card therein.

73. In a time recorder, printing mechanism, a card guide or receiver, a plurality of individually yielding stops located exterior thereto, and means to successively and progressively project said stops into the receiver, to limit the movement of a card when the latter is inserted in the receiver.

74. The combination with a time stamp, of a card receiver or guide, a series of individually spring-controlled stops located exterior thereto, and movable in unison and also relatively to each other, and means to effect automatically unison movement of the stops at predetermined intervals of time, to move one

stop after another toward operative position, the final positioning of each stop being effected by individual movement thereof.

75. The combination with recording means of a card guide, a series of stops to successively project into the path of a card in the guide, means to intermittently move said stops in unison to bring one stop after another toward operative position, and a spring

coöperating with each stop to snap it into 10 complete operative position.

In testimony whereof, I have signed my name to this specification, in the presence of two subscribing witnesses.

CHARLES T. HAWLEY.
